QUATERNARY SALTS OF DIALKYL THIOPHOSPHATE ESTERS

Howard M. Fitch, Millburn, N.J., assignor to Campbell Pharmaceuticals, Inc., New York, N.Y., a corporation of Delaware

No Drawing. Application January 15, 1958
Serial No. 708,966

14 Claims. (Cl. 260—461)

This invention relates to quaternary ammonium salts of dialkylaminoethyl thiophosphate esters and to the treatment of conditions of disease therewith.

The novel compounds of the invention are quaternary ammonium salts of dialkylaminoethyl thiophosphate esters of the general formula.

wherein R, R₁, and R₂ are alkyl groups, R₃ is hydrogen, alkyl or substituted alkyl, including dialkylaminoalkyl, X is sulfur or oxygen, at least one X being sulfur, and n is an integer from 1 to 3.

The compounds of the invention show a prolonged inhibition of cholinesterase, making them particularly suitable for causing a prolonged miosis and fall in intraocular pressure on topical application to the eye. The preferred compounds for such use are the quaternary ammonium salts of S-β-dialkylaminoethyl dialkyl thiophosphates and particularly of S-β-di-methylaminoethyl-O,O-diethyl thiophosphate. The compounds of the invention are also useful in the treatment of myasthenia gravis, preferably by oral administration.

The quaternary ammonium salts of the invention are also useful insecticidal agents.

One method for preparing the bases of the compounds of the invention comprises causing an alkali metal salt of a β-dialkylaminoethanol or a substituted β-dialkylaminoethanol to react with a thionophosphoryl halide. The alkali metal salt may be dissolved or suspended in an inert solvent, such as benzene, toluene, or the like, and an excess of the β-dialkylaminoethanol may in some cases be used to aid in solution of the alkali metal salt and facilitate the reaction. Relatively low reaction temperatures in the range of 3 to 30° C. are preferred, since the products tend to decompose at high temperatures. The thionophosphoryl halide may be a thionophosphoryl trihalide, a monoalkyl thionophosphoryl dihalide or a dialkyl thionophosphoryl monohalide, giving rise to products containing three, two or one β-dialkylaminoethyl ester groups, respectively. Crude mixtures of monoalkyl thionophosphoryl dihalides and dialkyl thionophosphoryl monohalides, obtained by causing a thionophosphoryl trihalide to react with an alcohol or an alkali metal alcoholate, may also be employed.

An alternative method comprises causing a β-halogenoethanol or an alkali metal β-halogenoetholate to react with a thionophosphoryl halide. The β-halogenoethyl ester thus obtained is caused to react with a trialkylamine, giving a quaternary ammonium halide salt of a β-dialkylaminoethyl thionophosphate. This method is most effective when the β-halogenoethanol is β-chloroethanol and is not suitable for preparing β-dialkylaminoethyl thiophosphates in the form of the free base or of a salt with an organic or inorganic acid.

The β-dialkylaminoethyl thiophosphates are typically colorless liquids or oils showing the usual chemical proper-

ties of tertiary aliphatic amines. They react readily with organic or inorganic acids to form salts and with alkyl halides or sulfates to form quaternary ammonium salts. The free bases tend to decompose on heating, particularly at temperatures above 100° C., although many of them can be distilled with relatively little decomposition at pressures of 1-2 mm. or less.

The β-dialkylaminoethyl thionophosphates of the formula

in general, readily isomerize to the corresponding thiols of formula

on heating, or even on standing at room temperature for long periods. While the thiol esters may be separated from the thionophosphates by physical methods, such as fractional crystallization, the facile rearrangement of the thionophosphates into the corresponding thiol esters makes it difficult to obtain or maintain the thionophosphates free of the isomeric thiol esters. Usually the thionophosphates as obtained by the methods of the invention will contain greater or lesser amounts of the isomeric thiol esters.

The amounts of the thiol ester contained in a thionophosphate preparation may readily be determined by hydrolysing the thiol ester with dilute alkali under mild conditions and titrating the hydrolysate idometrically for mercaptan under the following conditions:

An accurately weighed sample of 0.1 to 0.2 millimole is placed in 5 cc. 1 N sodium hydroxide solution. If the sample does not dissolve readily, 5 cc. of ethanol is added. After standing two hours at room temperature, the mixture is chilled in an ice bath and treated with 3 cc. of 6 N hydrochloric acid. A small lump (ca. 0.2 g.) of potassium iodide is added and the mixture is immediately titrated with 0.02 N potassium iodate solution to a permanent pale yellow end point. The mole percent thiol (i.e. the percent of thiol isomers in the sample of ester) is obtained by multiplying the molecular weight of the ester by twice the number of cc. 0.02 N potassium iodate required for the titration, and dividing by the weight of the sample in milligrams.

The thiol esters may also be prepared by causing an alkali metal salt of a dialkylaminoethylmercaptan to react with a phosphoryl halide or with a thionophosphoryl halide, or by causing a dialkylaminoethyl halide to react with a thiothionophosphate ester. The latter two procedures produce thiothionophosphate esters.

EXAMPLE I

β-Dimethylaminoethyl diethyl thionophosphate

To a solution of 53.5 g. β-dimethylaminoethanol (0.60 mole) in 200 cc. dry benzene is added 6.90 g. sodium (0.30 mole) with stirring during one-half hour. When the initial reaction has subsided, the mixture is stirred at 60-65° C. for about two hours until all the sodium has reacted. The solution of sodium β-dimethylaminoetholate thus obtained is cooled to about 3° C., and a solution of 56.6 g. diethyl thionophosphoryl chloride (0.30 mole) in 100 cc. dry benzene is added with stirring at 3-4° C. during two hours. The mixture is stirred and allowed to warm to room temperature during two addi-

tional hours, and is washed with 35 cc. and 10 cc. portions of water and with 25 cc. saturated brine and dried over anhydrous calcium sulfate. After removing calcium sulfate by filtration and solvent and excess β -dimethylaminoethanol by distillation at about 15 to 60 mm. pressure, the residue is distilled in vacuo. The product is 56.2 g. (78 percent theory) of crude β -dimethylaminoethyl thionophosphate as a colorless liquid boiling at 82-92° C./0.3 mm.

The acid oxalate salt, prepared in absolute alcohol by adding an equivalent of oxalic acid dihydrate and purified by crystallization from isopropanol, is obtained as large white plates, M.P. 131-2° C., containing about 0.8 mole percent of the isomeric thiol.

The methomethylsulfate, prepared by adding an excess of dimethylsulfate to a cold solution of the base in acetone and purified by crystallization from a 2 percent solution of isopropanol in ethylacetate, is obtained as flat, white needles, M.P. 92.5-3.5° C., containing about 3.8 mole percent of the isomeric thiol.

A suspension of 23.2 g. purified acid oxalate (0.07 mole) in 110 cc. water is treated with 15.0 cc. concentrated ammonium hydroxide and extracted with 150 cc. and then with 100 cc. ether. The ether extracts are combined, dried over calcium sulfate and filtered. The filtrate is stirred in an ice bath, and 9.34 g. dimethyl sulfate (0.074 mole) is slowly added. A precipitate forms rapidly. The mixture is left in an ice bath for two hours and at room temperature overnight and is filtered. The precipitate is 23.0 g. methomethyl sulfate (89 percent theory). Three crystallizations from a 2 percent solution of isopropanol in ethyl acetate yield 20.8 g. flat white needles, M.P. 92.5-94° C., containing no thiol isomer.

The methiodide, prepared by adding an excess of methyl iodide to a cold solution of the base in methanol, thrown out of solution by adding ether and purified by dissolving in isopropanol and precipitating with ether, is obtained in the form of the monohydrate as white plates, M.P. 114-7° C., containing about 9.4 mole percent of the isomeric thiol.

A solution of 5.0 g. purified acid oxalate (0.015 mole) in 35 cc. water is treated with 5.0 cc. concentrated ammonium hydroxide and extracted with 35 cc. benzene. The benzene extract is washed with saturated brine, dried over calcium sulfate and filtered. The filtrate is stirred in an ice bath, and 2.70 g. methyl iodide (0.019 mole) is slowly added. The mixture is left at room temperature overnight, diluted with 50 cc. 30-60° C. petroleum ether and filtered from 5.15 g. methiodide (90 percent theory). Two crystallizations from a solution of 10 percent isopropanol in ethyl acetate and one crystallization from a solution of 5 percent isopropanol in ethyl acetate yield 3.0 g. white plates, M.P. 117-9.5° C., containing 1.8 mole percent thiol isomer.

The methobromide, prepared by adding an excess of methyl bromide to a cold solution of base in acetone, thrown out of solution by adding ether and purified by dissolving in isopropanol and precipitating with ether, is obtained as very hygroscopic white needles, M.P. 76-81° C.

The methochloride, prepared by bubbling methyl chloride through a cold solution of the base in acetone, thrown out of solution by adding ether and purified by dissolving in isopropanol and precipitating with ether, is obtained as deliquescent white needles, M.P. 58-60° C.

EXAMPLE II

O,O -diethyl- S - β -dimethylaminoethyl thiophosphate

The reaction is carried out in an atmosphere of nitrogen. To a solution of 4.60 g. sodium (0.20 mole) in 60 cc. of methanol is added 14.17 g. β -dimethylamino-

ethyl mercaptan hydrochloride (0.10 mole), rinsed in with 10 cc. methanol. Solvent is removed at a water-pump vacuum while blowing with a slow stream of nitrogen to 100° C./20 mm. To the residue suspended in 150 cc. benzene and cooled in an ice bath is added 17.25 g. diethylchlorophosphate (0.10 mole) in 3 portions at 10 minute intervals. After each addition, the temperature increases from about 4 to about 14° C. and then falls. The mixture is stirred in an ice bath for one-half hour and while warming to room temperature during 2 hours is washed with 35 and 5 cc. portions of water with two 10 cc. portions of saturated brine and is dried over calcium sulfate and filtered. After removal of solvent by distillation under reduced pressure to 55° C./20 mm., the residue is 23.0 g. crude base (95 percent theory) as a pale yellow liquid. A sample of the crude base distills with some decomposition at 105-12° C./0.8 mm.

A sample of the crude base in isopropanol is treated with excess oxalic acid dihydrate, heated to boiling and 20 filtered hot from insoluble material. The acid oxalate salt precipitates from the filtrate on cooling and dilution with several volumes of ether. It is purified by crystallization from mixtures of isopropanol and ether and isopropanol and ethyl acetate and from isopropanol alone. 25 The pure acid oxalate is obtained as a white solid, M.P. 111-1.5° C., gas evol., containing 97 mole percent thiol isomer.

A sample of distilled base in cold isopropanol is treated with excess methyl iodide, left at room temperature overnight, diluted with 5 volumes of ethyl acetate, and filtered from the methiodide salt. This is purified by crystallization from mixtures of isopropanol and ethyl acetate, filtering hot to remove an impurity of low solubility. The pure methiodide is obtained as a white solid, 35 M.P. 124-4.5° C., containing 99 mole percent thiol isomer.

EXAMPLE III

β -Dimethylaminoethyl dimethyl thionophosphate

The base, prepared as described in Example I from sodium β -dimethylaminoethylate and dimethyl thionophosphoryl chloride, is obtained as a colorless liquid, B.P. 64-5° C./0.4 mm. The acid oxalate crystallizes from absolute alcohol as white plates, M.P. 111-2° C., free from thiol isomer. The methiodide crystallizes from isopropanol as the sesquihydrate, M.P. 96-7° C. gas evolution, containing about 5.4 mole percent of thiol isomer.

EXAMPLE IV

β -Dimethylaminoethyl di-n-propyl thionophosphate

The base, prepared as described in Example I from sodium β -dimethylaminoethylate and di-n-propyl thionophosphoryl chloride, is obtained as a colorless liquid boiling at 92-112° C./0.3 mm. The acid oxalate crystallizes from a mixture of isopropanol and ether as white plates, M.P. 122-4° C., containing about 2 mole percent of thiol isomer. The methiodide crystallizes from a mixture of isopropanol and ether as fine white needles, M.P. 100-3° C., containing about 9 mole percent of thiol isomer.

EXAMPLE V

β -Dimethylaminoethyl di-isopropyl thionophosphate

The base, prepared as described in Example I from sodium β -dimethylaminoethylate and di-isopropyl thionophosphoryl chloride, is obtained as a colorless liquid,

B.P. 83-93° C./0.6 mm. The methiodide crystallizes from a mixture of isopropanol and ether as fine white needles, M.P. 121.5-3° C., gas evolution, containing about 1.4 mole percent of the thiol isomer.

EXAMPLE VI

 β -Dimethylaminoethyl di-n-butyl thionophosphateThe base, prepared as described in Example I from sodium β -dimethylaminoethylate and di-n-butyl thionophosphoryl chloride, is obtained as a colorless liquid, B.P. 103-20° C./0.3 mm. The acid oxalate crystallizes from isopropanol as white plates melting indefinitely at 101-13° C., containing about 3.7 mole percent of the thiol isomer. The methiodide crystallizes from a mixture of benzene and 30-60° C. petroleum ether as fine somewhat waxy crystals, M.P. 77-9 C., containing about 7.2 mole percent of the thiol isomer. 22.7 grams of crude undistilled base (0.076 mole) is added to a solution of 10.1 g. oxalic acid dihydrate (0.08 mole) in 100 cc. isopropanol. On dilution with 400 cc. ether a copious precipitate forms. This is filtered off and crystallized three times by dissolving in 100 cc. hot isopropanol, adding 250 cc. hot ethyl acetate, cooling and filtering. 14.8 grams of purified acid oxalate is obtained as large white plates, M.P. 101.5-2.5° C., containing no thiol isomer.

5.81 grams of the pure acid oxalate (15 millimoles) in 50 cc. water is treated with 18 cc. 2 N ammonium hydroxide solution and extracted with 50 cc. benzene. The benzene extract is washed with 10 cc. saturated brine, dried over calcium sulfate and filtered. To the filtrate is added 2.55 g. methyl iodide (18 millimoles). After standing at room temperature overnight, the solution is diluted with 300 cc. 30-60° C. petroleum ether and filtered. The precipitate is purified by crystallization from mixtures of ethyl acetate and 30-60° C. petroleum ether and from ethyl acetate alone, yielding 4.51 g. pure methiodide as flat white needles, M.P. 93-4° C., containing no thiol isomer.

EXAMPLE VII

O,O-di-n-butyl-S- β -dimethylaminoethyl thiophosphateThis compound is prepared from the sodium salt of β -dimethylaminoethyl mercaptan and di-n-butyl chlorophosphate as described in Example II. The acid oxalate salt, purified by repeated crystallization from mixtures of isopropanol and ether and of ethyl acetate and 30-60° C. petroleum ether (filtering hot from some insoluble material), is obtained as deliquescent waxy white plates, M.P. 89-94° C., containing 100 percent thiol isomer. The methiodide, prepared from the purified oxalate and crystallized from mixtures of ethyl acetate and 30-60° C. petroleum ether and of benzene and 30-60° C. petroleum ether, is obtained as a deliquescent white solid, M.P. 83-7° C., containing 95.5 percent thiol isomer.

EXAMPLE VIII

 α -Methyl- β -dimethylaminoethyl diethyl thionophosphateThe base, prepared as described in Example I from the sodium salt of 1-dimethylamino-2-propanol and diethyl thionophosphoryl chloride, is obtained as a colorless liquid, B.P. 77-87° C./0.5 mm. The acid oxalate, crystallized from isopropanol, melts at 120-1° C., and is free from thiol isomer. The methiodide, crystallized from isopropanol, melts at 134-5° C. and is free from thiol isomer.

EXAMPLE IX

1,3-bisdimethylamino-2-propyl diethyl thionophosphate

The sodium salt of 1,3-bisdimethylamino-2-propanol is prepared by adding 9.80 g. 1,3-bisdimethylamino-2-propanol (0.067 mole) to a solution of sodium methylate obtained by dissolving 1.54 g. sodium (0.067 mole) in 25 cc. methanol. Methanol is removed by distillation under reduced pressure, the last traces of methanol being removed at 100° C./0.5 mm. To the residual sodium salt suspended in 100 cc. benzene is added a solution of 12.65 g. diethyl thionophosphoryl chloride (0.067 mole) in 50 cc. benzene with stirring at 3-5° C. during about one hour. The mixture is stirred for an additional hour in an ice bath and during three hours while slowly warming to room temperature and left overnight. After washing with 10 cc. and 3 cc. portions of water and with 15 cc. saturated brine and drying over anhydrous calcium sulfate, solvent is removed by distillation under reduced pressure to 100° C./10 mm. The residue is 14.45 g. dark amber oil. This is placed in 350 cc. ether, let stand for three days and filtered from ether-insoluble material. The residue after distillation of ether from the filtrate is 8.60 g. amber liquid. This on treating a solution in 60 cc. isopropanol with 7.60 g. oxalic acid dihydrate and precipitating by adding ether gives 8.73 g. crude oxalate salt. Purification by several crystallizations from absolute alcohol gives the di-acid oxalate as white crystals, M.P. 114-5° C., containing about 1.6 mole percent of thiol isomer. A sample of the di-acid oxalate converted to the base and treated with methyl iodide gives the methiodide, which on purification by crystallization from absolute alcohol is obtained as white needles, M.P. 136.5°-8.5° C., gas evol., containing about 4.6 mole percent of thiol isomer.

EXAMPLE X

Di-(β -dimethylaminoethyl) ethyl thionophosphateThis compound is prepared from two moles of sodium β -dimethylaminoethylate and one mole of ethyl thionophosphoryl dichloride as described in Example I, except that the base is not distilled. The di-acid oxalate, crystallized from 95 percent alcohol and from a mixture of absolute alcohol and methanol, is obtained as white crystals, M.P. 148-9° C., gas evol., containing about 1.6 mole percent of thiol isomer. The dimethiodide, crystallized from a mixture of absolute alcohol and methanol, is obtained as white crystals containing two molecules of water, M.P. 156-68° C., decomposition, containing about 35 mole percent of thiol isomer.

EXAMPLE XI

Di-(β -dimethylaminoethyl) isopropyl thionophosphateThis compound is prepared from sodium β -dimethylaminoethylate and isopropyl thionophosphoryl dichloride as described in Example X. The di-acid oxalate, crystallized from absolute alcohol, is obtained as white crystals, M.P. 156-8° C., gas evolution, containing about 1 mole percent of thiol isomer.

EXAMPLE XII

Di-(β -dimethylaminoethyl) n-octyl thionophosphateThis compound is prepared from sodium β -dimethylaminoethylate and n-octyl thionophosphoryl dichloride

7
as described in Example X. The dimethiodide, crystallized from a mixture of isopropanol and ethyl acetate, is obtained as white crystals, M.P. 167-72° C., gas evolution, containing about 4 mole percent of thiol isomer.

EXAMPLE XIII

Tri-(β -dimethylaminoethyl) thionophosphate

To 44.6 g. β -dimethylaminoethanol (0.50 mole) in 200 cc. benzene is added 10.59 g. sodium (0.46 mole). When the initial reaction has subsided, the mixture is stirred at 75-83° C. under reflux for about five hours until all the sodium has reacted. After cooling, 25.40 g. thiophosphoryl chloride, 0.15 mole) in 50 cc. benzene is added with stirring at 4-8° C. during 1½ hours. The mixture is stirred while warming to room temperature during three hours, left overnight, stirred for eight hours longer, and left for three days at room temperature. After washing with 100 cc. and two 25 cc. portions of water and with 20 cc. saturated brine and drying over anhydrous calcium sulfate, solvent is removed by distillation under reduced pressure to 80° C./60 mm. The residue is 30.1 g. of crude base as a yellow liquid.

The tri-acid oxalate salt, purified by repeatedly dissolving in hot 50 percent alcohol and precipitating by adding 95 percent alcohol or absolute alcohol and cooling, crystallizes with three molecules of water as voluminous white needles, M.P. 130-2° C., containing about 1.2 mole percent of thiol isomer. The trimethiodide, purified in the same manner, crystallizes with three molecules of water as white crystals that darken at about 185° C. and melt at 201-3° C., gas evolution, containing about 8.2 mole percent of thiol isomer.

The pure base, obtained by treating the purified tri-acid oxalate with excess ammonium hydroxide and extracting into ether, is a colorless liquid, n_{D}^{25} 1.4708. The base decomposes with a vigorous exothermic reaction on being heated to around 125° C. and decomposes on attempted distillation in vacuum.

EXAMPLE XIV

β -Diethylaminoethyl diethyl thionophosphate

The base, prepared as described in Example I from sodium β -diethylaminoethylate and diethyl thiophosphoryl chloride, is obtained as a colorless liquid, B.P. 103-6° C./0.3 mm.

EXAMPLE XV

S- β -diethylaminoethyl-O,O-diethyl thiophosphate

The acid oxalate, prepared from the distilled base of Example XIV and crystallized from a mixture of isopropanol and ether and from methyl ethyl ketone, is obtained as white crystals, M.P. 83-8° C., containing 70 mole percent of the thiol isomer. The methomethyl sulfate, prepared from the acid oxalate and crystallized from a mixture of acetone and ethyl acetate, is obtained as a hygroscopic white solid, M.P. 72-4° C., containing 97 mole percent of the thiol isomer.

EXAMPLE XVI

β -Dimethylaminoethyl ethyl n-butyl thionophosphate

The base, prepared as described in Example I from sodium β -dimethylaminoethylate and ethyl n-butyl thiophosphoryl chloride, is obtained as a colorless liquid, B.P. 86-96° C./0.2 mm. The acid oxalate crystallizes from isopropanol as white plates, M.P. 107.5-8.5° C., containing about 1 mole percent of thiol isomer. The methiodide,

8
crystallized from a mixture of benzene and 30-60° C. petroleum ether, melts at 98.5-100° C. and contains about 8 mole percent of thiol isomer.

EXAMPLE XVII

β -Dimethylaminoethyl di-n-amyl thionophosphate

10 The base is prepared as described in Example I from sodium β -dimethylaminoethylate and di-n-amyl thiophosphoryl chloride. The acid oxalate, prepared from undistilled base and purified by crystallization from isopropanol, is obtained as a white solid, M.P. 106-7.5° C., containing no thiol isomer.

EXAMPLE XVIII

β -Dimethylaminoethyl di-n-octyl thionophosphate

20 The base is prepared as described in Example I from sodium β -dimethylaminoethylate and di-n-octyl thiophosphoryl chloride. The acid oxalate, prepared from undistilled base and purified by crystallization from a mixture of ethyl acetate and ether and from ethyl acetate, is obtained as a white solid, M.P. 102-6° C., containing no thiol isomer.

EXAMPLE XIX

30 O,O-diethyl-S- β -dimethylaminoethyl thiothionophosphate

35 This compound is prepared from the sodium salt of β -dimethylaminoethyl mercaptan and diethyl thiophosphoryl chloride as described in Example II. The acid oxalate, prepared from undistilled base and purified by crystallization from a mixture of isopropanol and ethyl acetate (filtered hot from some material of low solubility), is obtained as white plates, M.P. 118.5-9.5° C. The methiodide, prepared from the purified oxalate and crystallized from a mixture of isopropanol and ethyl acetate, is obtained as large white plates, M.P. 111-2° C., gas evol.

Ethiodide, white needles, M.P. 90-90.5° C. with gas evolution.

2-phenylethiodide, very viscous oil.

Benzylbromide, very hygroscopic waxy white crystals, M.P. 55-65° C. with gas evolution.

3,4-dichlorobenzylchloride, white solid, M.P. 198-199° C. with gas evolution.

p-Nitrobenzylchloride, white solid, M.P. 202-203° C. with gas evolution.

From the base of Example XIV—

Methomethylsulfate, hygroscopic white solid, M.P. 72-74° C.

From the oxalate of Example XX—

Methiodide, white plates, M.P. 121-122° C. with gas evolution.

In the treatment of glaucoma, topical application of aqueous solutions of the quaternary salts of the invention has been found to be effective in reducing intraocular tension. For example, 0.1% and 0.25% solutions of the S-β-dimethylaminoethyl-O,O-diethylthiophosphate methiodide of Example II in isotonic saline solution have been found to be useful in controlling intraocular tension in glaucomatous eyes. In particular, this compound has been found to have a longer duration of action than any of the commonly used miotics.

This application is a continuation-in-part of my now abandoned application Serial No. 533,495, filed September 9, 1955, which is a continuation-in-part of my now abandoned application Serial No. 509,096, filed May 17, 1955.

I claim:

1. The quaternary salts of di-lower alkylaminoethyl thiophosphate esters of the general formula

wherein R, R₁ and R₂ are lower alkyl groups, R₃ is selected from hydrogen, lower alkyl, and di-loweralkylaminoloweralkyl, X is selected from sulfur and oxygen

30

35

40

at least one X being sulfur, and n is an integer from 1 to 3.

2. A quaternary salt of an S-β-di-loweralkylaminoethyl-O,O-di-loweralkyl thiophosphate.

5 3. A quaternary salt of an S-β-dimethylaminoethyl-O,O-di-loweralkyl thiophosphate.

4. A quaternary salt of an S-β-dimethylaminoethyl-O,O-diethyl thiophosphate.

5. S - β - dimethylaminoethyl - O,O - diethylthiophosphate methiodide.

6. A quaternary salt of an S-β-dimethylaminoethyl-O,O-dibutyl thiophosphate.

7. S - β - dimethylaminoethyl - O,O - dibutylthiophosphate methiodide.

15 8. A quaternary salt of an S-β-di-loweralkylaminoethyl-O,O-di-loweralkyl thionophosphate.

9. A quaternary salt of an S-β-diethylaminoethyl-O,O-diethyl thiophosphate.

10. S - β - diethylaminoethyl - O,O - diethylthiophosphate methomethylsulfate.

11. A quaternary salt of an S-β-dimethylaminoethyl-O,O-diethyl thionophosphate.

12. S - β - dimethylaminoethyl - O,O - diethylthiophosphate methiodide.

25 13. A quaternary salt of a β-di-loweralkylaminoethyl-di-loweralkyl thionophosphate.

14. β-Dimethylaminoethyl diethylthiophosphate methiodide.
